COMPOSITE SIGNALING SYSTEM

James B. McKim, New York, N. Y., assignor to
 Bell Telephone Laboratories, Incorporated,
 New York, N. Y., a corporation of New York

Application July 26, 1933, Serial No. 682,195

6 Claims. (Cl. 179—3)

This invention relates to signaling systems and more particularly to duplex composite telephone and telegraph systems.

An object of the invention is to extend the signaling range of such systems over relatively high resistance line conductors without the use of supersensitive or critical electromagnetic devices.

A feature of the invention whereby the foregoing object is attained resides in the substitution of gas-filled discharge devices for the polarized electromagnetic relays previously employed in such systems, said discharge devices operating on line potential variations transmitted over the line. These discharge devices are connected to the line and the respective terminal sources of signaling potential by means of a properly arranged resistance network whereby any variation of the line potential occasioned by a change in either terminal source, as for example, by a reversal of polarity, will cause a change only in the potential of the control electrode of the distant discharge device in such a direction as to cause it to start discharging, the discharge device at the near end of the line remaining inert.

Still another feature resides in an arrangement comprising a thermionic tube associated with the control electrode of the discharge device and controlled over a pilot channel adjacent to and subject to the same earth potential as the signal channel whereby an equalizing bias is applied to the control electrode of the discharge device to compensate for the voltage changes in the signaling line due to said earth potential.

A complete understanding of the operation of the system contemplated by the invention as well as an appreciation of its various features may be gained from a consideration of the following detailed description and the annexed drawing.

Referring now to the drawing, there is shown a two-way composite trunk system extending between two stations, A and B. The trunk terminates at office A in jack 3 and at office B in jack 4. The alternating current telephone signals are transmitted between the stations over conductors 1 and 2 in the usual manner, condensers 5 and 6 at office A and 7 and 8 at office B presenting a low impedance path for these signals.

For the initiation of the direct current signals to be transmitted over a composite leg of the system, relay 9 is provided at office A and relay 10 at office B. Means for controlling the operation of these relays are provided at each office and are indicated schematically at 11 and 12, respectively. The direct current signals may be used for telegraphy in which instance telegraph keys may be provided to control the operation of relays 9 and 10. Again, it may be desirable to transmit a direct current signal for supervisory purposes during the setting up of the telephone connection in which instance the control of relays 9 and 10 may

reside in other relays (located within the rectangles 11 and 12) operating, for example, over the sleeve circuits of the respective jacks 3 and 4.

Sources of negative potential, 21 and 13, respectively, are associated with the armature circuits of relays 9 and 10 as are also resistance networks comprising, at station A, resistances 15, 16 and 17 and at station B, resistances 18, 19 and 20.

The direct current signal receiving set provided at station A includes a gas-filled discharge tube 23, a pair of polarized relays 24 and 25 and a lamp 26. Each of the relays is provided with two windings, an upper or "operating" winding and a lower or "biasing" winding. Current normally flows from battery 69 through the "biasing" winding of each relay in such a direction that their armatures are normally held in a released condition. Gas-filled tube 23 is of the type frequently referred to as a "trigger" or tube and may, for example, be constructed as described in Patent No. 1,921,004, issued Aug. 8, 1933, to A. L. Samuel. According to the characteristics of tubes of this type, for a given plate voltage, a negative grid bias below a given voltage will prevent the passage of plate current. Upon a sufficient change of the grid bias in a positive direction however, the plate circuit passes current, ionization of the gas in the tube occurs, that is, the tube "breaks down" as it is commonly stated, and the grid loses control. The discharge in the tube, once started, persists until the positive plate current is interrupted.

A vacuum tube 31 (not a "trigger" tube) is also associated with the direct current signal receiving set for a purpose and operating in a manner to be subsequently described in detail.

The direct current signal receiving set at station B is similar to that of station A and includes "trigger" tube 27, polarized relays 28 and 29, lamp 30 and vacuum tube (not a "trigger" tube) 32.

Retardation coils 35 and 75 are connected in the line at station A and retardation coils 36 and 76 are connected in the line at station B, the windings thereof providing a low impedance path for direct current signals received over conductors 45, 46, 47 or 48 and at the same time, due to their inductance, preventing passage of the alternating current telephone signals into the direct current signal sending and receiving portions of the system. A low impedance path to ground is provided through condensers 37, 38, 39, 40, 41, 42, 43 and 44 for the small amount of alternating current that may traverse the windings of the retardation coils.

Let us now assume, for purposes of illustration, that, in order to transmit a direct current signal from station A to station B, the means provided within the rectangle 11, for controlling relay 9, be operated.

Normally, i. e. when relay 9 is in its unoperated position, a negative bias from battery 21 is applied to the grid of "trigger" tube 27 of sufficient value to prevent the tube from discharging. This negative bias is applied through a circuit traced from battery 21, upper break contact of relay 9, resistance 15, conductor 45, lower winding of retardation coil 35, line conductor 2, lower winding of retardation coil 36, conductor 47, resistance 19 to the grid of tube 27.

It should be here pointed out that the ratios of resistances 15, 16 and 17 of the network at station A and the corresponding resistances 18, 19 and 20 at station B of respective equal values are such with respect to each other and to the line resistance that any potential variation at either station will be effective to vary, in a positive direction, the potential applied to the grid of the "trigger" tube at the distant station only and will cause no change, in a positive direction, in the potential applied to the grid of the "trigger" tube at the near or home station.

Assuming now that, due to operation of means included within rectangle 11, relay 9 be operated, the source of negative potential 21 is removed from line 2 and ground 22 is connected thereto. Upon removal of the negative potential from the line, the potential of the grid of tube 27 becomes less negative by such an amount that the tube "breaks down" and discharges. No change in a positive direction occurs in the potential applied to the grid of tube 23 however due to the relative values of resistances 15, 16 and 17, referred to above.

As tube 27 "breaks down" and the space current path is set up current flows through the upper or "operating" windings of relays 28 and 29 in the proper direction to cause both relays to operate. The ratio of the resistances of the "operating" and "biasing" windings of the relays is such that the effect of the current normally flowing through the "biasing" windings is overcome by the current now passing through the "operating" windings and the relays operate. Operation of relay 29 completes a circuit from battery 64, lamp 30, make contact of relay 29 to ground 65, lamp 30 being energized over this circuit and serving as an indication of the operation of relay 9 at station A.

Now as relay 28 operates it completes a path through lead 71 and the armature of relay 28 which acts to short circuit the upper or "operating" winding of relay 28 and the plate of discharge tube 27. Relay 29 is held operated over this path while the discharge in tube 27 is interrupted, due to the short circuiting of the plate, and control of the tube is returned to the grid. As current in the upper winding of relay 28 is interrupted the armature moves to its "released" position by virtue of the current flowing through the lower or "biasing" winding, thereby removing the short circuit from the plate of tube 27. Assuming that, when the discharge in tube 27 is interrupted and control of the tube returned to the grid, relay 9 is still operated, tube 27 immediately "breaks down" again and relay 28 again operates. This cycle is repeated at a rapid rate, relay 28 in effect "buzzing" and causing the discharge in tube 27 to alternately start and stop at the same rate. Relay 29 remains steadily operated during the buzzing action of relay 28.

The intermittent operation of tube 27 and relay 28 continues until relay 9 restores to normal whereupon, as the discharge in tube 27 is interrupted as above described, the grid of the tube is

held at a sufficiently negative bias by virtue of source of negative potential 21, now applied to the line, that the tube does not again "break down" as relay 28 releases. The armature of relay 29 thereupon moves to "released" position by virtue of the current through the lower or "biasing" winding and lamp 30 is extinguished.

It will be apparent from the above description that operation of relay 9 at station A causes energization of lamp 30 at station B and that the lamp remains energized as long as relay 9 remains operated. Return of relay 9 to normal condition results, in turn, in the deenergization of lamp 30. If desirable a locking relay circuit may be inserted between the armature circuit of relay 29 and lamp 30 whereupon lamp 30 will remain energized after the release of relay 29. The locking circuit may be any of the ordinary and well known arrangements and has not been shown in the drawing.

Lamp 26 at station A is, in a manner similar to that just described in connection with the energization of lamp 30 at station B, energized upon the operation of relay 10 at station B and remains in energized condition until the relay returns to normal position.

In view of the fact that, as stated above, the ratio of the resistances of the network associated with each relay (15, 16 and 17 at station A and 18, 19 and 20 at station B) is such that the position, "operated" or "normal", of the respective relays has no effect on the condition of the "trigger" tube at the same station, it will be apparent that the system provides "two-way" operation, i. e., signals may be sent from A to B without affecting lamp 26 and from B to A without affecting lamp 30. The response of relay 29 to incoming signals is not affected by the condition of relay 10 in transmitting signals nor is the response of relay 25 affected by the condition of relay 9.

In order to prevent variations in earth potential between the two ends of the line from affecting the operation of the circuit, means have been provided at each station for equalizing the effects of such variations. A vacuum tube and associated circuit are provided at each station (31 at station A and 32 at station B) and are connected through respective leads 46 and 48 to conductor 1 which is adjacent to and subject to the same variations in earth potential as conductor 2.

Referring to station A, the output of vacuum tube 31 is affected by the same variation in earth potential applied to the grid over conductor 46 as that which is applied to the grid of discharge tube 23 over conductor 45. The voltage drop across resistance 51 is applied to the grid of tube 23 through resistance 50. This potential varies as the output of tube 31 is varied by the variation in earth potential applied to the grid. The ratio of resistances 50, 51 and 52 is such that variations in earth potential in line 1 will so vary the output of tube 31 and the potential applied thereby to the grid of tube 23 that the effect on the grid of tube 23 of the same variations in earth potential in conductor 2, is neutralized.

Tube 32 and associated circuit at station B act in a similar manner to neutralize the effect of variations in earth potential on the grid of tube 27.

While one specific embodiment of the invention has been selected for detailed description the invention is not limited in its application to such a system. The invention is intended

to be limited only as indicated by the attached claims.

What is claimed is:

1. In a duplex signaling system, a line, a grounded source of potential at each end of the line, a resistance network connected in parallel with each potential source, a connection between each end of the line and a point in its respective network, transmitting means at each end of the line for varying the potential of the line, a gas-filled discharge tube comprising a control electrode associated with each network, a connection between each control electrode and its associated network at another point therein, a signal receiving device controlled by each discharge tube, a pilot line adjacent to said signaling line and subject to the same earth potential, a thermionic device at each end of said pilot line and controlled thereover, and a connection including a high resistance between the output of each thermionic device and the control electrode of its respective discharge device whereby the control electrodes are subjected to an equalizing bias to compensate for potential variations 25 in the signaling line due to earth potential.
2. In a direct current duplex signaling system, a line circuit, a resistance network at each end thereof, a space discharge device including a control electrode at each end of the line, a connection between each control electrode and an intermediate point in the network at the same end of the line, a connection between each end of the line and two other points in the network thereat, a source of direct current connected in parallel with each network, said sources being so poled with respect to the network and said intermediate network points so chosen that a predetermined negative bias normally exists on said control electrodes, a signal receiver associated with each discharge device and controlled thereby, and transmitting means at each end of the line for varying the potential of the source thereat to decrease the negative bias on the control electrode of the distant end 45 of the line and prevent any change in a positive direction on the near electrode whereby the distant discharge device only is caused to operate its associated receiver.
3. In a direct current duplex signaling system, a line conductor, a resistance network at each end thereof, a space discharge device including a control electrode at each end of the line, a connection between each control electrode and an intermediate point in the network at the same end of the line, a connection between each end of the line conductor and another intermediate point in the associated network, a grounded source of direct current connected in parallel with each network, said intermediate connections being so chosen and said grounded sources so poled that a predetermined negative bias normally exists on the control electrodes at both ends of the line, a signal receiver associated with each discharge device and controlled thereby, and transmitting means at each end of the line for varying the potential of the source thereat to decrease the negative bias on the control electrode at the distant end of the line and prevent any change in a positive direction on the near electrode whereby the distant discharge device only is caused to operate its associated receiver.
4. In a direct current duplex signaling system, a line conductor, a signaling station at each end thereof, a grounded source of direct current at each station, a high impedance circuit in shunt to each source, said circuit including a high resistance and a relatively low resistance, a gas-filled discharge device including a control electrode at each station, a circuit for each discharge device so arranged that the device is inactive when the potential of its electrode is below a predetermined critical value, a connection between each end of the line conductor and the junction of the high and low resistances at that station, a connection between each control electrode and an intermediate point in the associated high resistance, a signal receiving device controlled by each discharge device, said current sources being so poled with respect to the line and said control electrodes being connected at such points in the high resistances that normally both control electrodes are below the predetermined critical value at which the discharge device becomes active, and transmitting means at each station for reversing the grounded source thereat with respect to the high resistance and line conductor to raise the potential of the control electrode at the distant station only above said critical value.
5. In a direct current duplex signaling system, two signaling stations, a source of direct current at each station having their positive poles grounded, a high resistance and a relatively low resistance in shunt to each source, a receiving circuit including a gas-filled discharge tube at each station, a control electrode for each tube, a connection between each electrode and an intermediate point in its associated high resistance, said intermediate point being so chosen that the connected control electrode normally has a predetermined negative bias with respect to ground, a line conductor connected to junctions of the high and low resistances of each station, and transmitting means at each station for grounding the line conductor through the low resistance thereat to raise the potential of the control electrode at the distant station and thereby energize the receiving circuit.
6. In a direct current signaling system, a transmitting station and a receiving station, a grounded source of direct current at the receiving station, a shunt circuit connected across said source including a high resistance and a relatively low resistance, a line conductor extending between said stations and connected to the junction of the high and low resistances at the receiving station, a gas-filled discharge tube including a control electrode at the receiving station, a connection between the control electrode and an intermediate point in the high resistance, said point being so chosen and said source so poled with respect to the shunt circuit that a predetermined negative potential bias with respect to ground normally exists on the control electrode, a receiving device controlled by said discharge tube and adapted to be operated when the control electrode potential is raised above said normal bias, a resistance at the transmitting station equal to the low resistance at the receiving station, and means at the transmitting station for grounding said line conductor through the resistance thereat to raise the potential of the control electrode at the receiving station and operate the receiving device.

JAMES B. MCKIM.
